ANNEALING FURNACE

Robert Gilmore Le Tourneau, Peoria, Ill., assignor to R. G. Le Tourneau, Inc., Stockton, Calif., a corporation of California

Application December 28, 1942, Serial No. 470,353

3 Claims. (Cl. 263—43)

This invention relates to annealing furnaces; it being the principal object of the invention to provide an annealing furnace which includes a floor assembly and a separate hood assembly, here illustrated of dome-shaped configuration, seated on the floor assembly and forming therewith an enclosed fire chamber; the hood assembly being removable, by means such as a crane, to permit of placement of the work on, or removal thereof from, said floor assembly.

An additional object of this invention is to provide an annealing furnace as in the preceding paragraph in which said furnace includes a unique venting arrangement for the gases of combustion; such arrangement including a central flue opening in the floor assembly, and a horizontal flue disposed beneath the floor and communicating with said opening.

It is also an object of this invention to provide an annealing furnace which includes, in combination with a floor assembly and a separate and removable hood assembly, novel sealing means between said assemblies when in engagement; said sealing means including an annular, downwardly projecting lip on the hood assembly seating in an upwardly opening annular trough on the floor assembly, said trough having a bed of granular fire-resistant material, such as sand, therein.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a sectional elevation of the improved annealing furnace.

Figure 2 is a sectional plan of reduced size, partly broken away, taken on line 2—2 of Fig. 1.

Referring now more particularly to the characters of reference on the drawings, the numeral 1 indicates a horizontal base ring of substantial diameter and formed of inwardly facing channel iron, said ring being seated on the ground 2.

The floor assembly of the furnace is mounted on top of the base ring and comprises a circular metallic floor plate 3 of slightly greater diameter than the base ring 1, and seated concentrically thereon. Adjacent its periphery the circular floor plate 3 is fitted with an upwardly opening annular trough 4; said trough being of channel

5 form in section and having a sand bed 5 in the bottom thereof. Inwardly of the annular trough 4 the floor plate 3 is covered with a layer 6 of fire resistant vermiculite plaster; a floor 7 of fire brick being formed on top of said layer of plaster. Ring 1 and member 4 are heat resistant steel, cast in segments.

10 A flue opening 8 extends centrally through the floor plate 3, layer 6 and fire brick floor 7. A horizontal flue is disposed between the floor plate 3 and ground 2, and extends from the flue opening, with which it communicates, radially through the base ring 1 to connection laterally outwardly of the furnace with a stack (not shown).

The hood assembly, which cooperates with the above described floor assembly, comprises the following:

15 A dome-shaped outer shell 10 having a diameter at the bottom greater than the diameter of annular trough 4, is normally disposed above and supported by the floor assembly. An annular, horizontal shelf 11, here shown as comprising two annular plates bolted together as at 12 20 in overlapping relation, is secured to the lower end of the dome-shaped shell 10 and extends radially inwardly therefrom in overhanging relation to the annular trough 4. An annular lip 13 is formed on and depends from the inner edge 25 of shelf 11, said lip seating on the sand bed 5 in said trough 4 whereby the dome assembly is supported concentrically by the floor assembly. The sand bed 5 forms a seal between the lip 13 and the trough 4 to prevent undesired escape of the 30 gases of combustion from the enclosed fire chamber 14, which is formed by the floor and hood assemblies when in engagement.

35 The outer shell 10 is provided with an inner lining 15 of fire resistant vermiculite plaster; the shelf 11 preventing displacement of said lining from the shell. The interior side wall of the dome-like hood assembly above described is lined with fire brick 16, which lining extends from the shelf 11 vertically upward a distance approximately half the diameter of the dome. Burner ports 17, generally tangentially disposed, are formed in the dome-like hood assembly at circumferentially and symmetrically spaced points. Burners 18 project into said ports, and fuel is fed 40 to said burners by slack, flexible conduits (not shown).

45 Circumferentially spaced lifting loops 19 are fixed to the shell 10 exteriorly thereof; said loops being adapted for connection to a multiple lead hoist chain or cable (not shown), which is 50

operative to lift the dome-like hood assembly vertically relative to and clear of the floor assembly, to permit of placement of work on the floor 7, or removal of the work therefrom after an annealing operation.

In operation, when the dome-like hood assembly is seated in sealed relation on the floor assembly, work disposed on the fire brick floor 7 is exposed directly to the heat from the burners 18; all gases of combustion passing downwardly through the flue openings 8 and thence escaping from the furnace through the horizontal flue 9. This flue opening and flue arrangement in and below the bottom of the furnace assures maximum efficiency of the furnace and a minimum B. t. u. loss.

As the dome-like hood assembly is removable from the floor assembly, the work may be readily placed on or removed from the latter, even though the work may be bulky and weighty.

To support and reinforce the plaster 15 depending hooks 20 are welded on the shell 10 before the plaster is applied, wire 21 extending between and supported by the hooks serving as a further support for the plaster.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An annealing furnace comprising a metallic floor plate of circular configuration, means supporting said plate horizontally, a circular floor of fire resistant material formed on said plate in concentric relation thereto, the floor being of lesser diameter than the plate, an annular upwardly opening trough on the plate in surrounding relation to said floor, means securing the trough to said plate, an initially separate dome-like hood assembly disposed symmetrically above and forming with said floor an enclosed fire chamber, and a depending annular lip on the hood seating in said annular trough in supporting relation to the hood, the trough having a bed of fire resistant material therein.
2. An annealing furnace comprising a metallic floor plate of circular configuration, a concentric base ring supporting the plate horizontally, a circular floor of fire resistant material formed on the plate in concentric relation, the plate being of greater diameter than the base ring and floor and extending radially out beyond the peripheries thereof, an annular upwardly opening trough on the plate in surrounding relation to said floor, securing bolts extending from the trough through the plate radially outwardly relative to said base ring, an initially separate dome-like hood assembly disposed symmetrically above and forming with said floor an enclosed fire chamber, and a depending annular lip on the hood seating in said annular trough in supporting relation to the hood, the trough having a bed of fire resistant material therein.
3. An annealing furnace as in claim 2 in which said trough is segmental whereby to facilitate removal and replacement thereof.

ROBERT GILMORE LE TOURNEAU.
